INVENTOR.

MCREE GREEN
BY
Henry Kinney,
ATTORNEY.

UNITED STATES PATENT OFFICE

MCREE GREEN, OF ST. LOUIS, MISSOURI

WEATHER STRIP STRUCTURE

Application filed January 27, 1930. Serial No. 423,818.

My invention relates to weatherstrip structures and more particularly to metal weatherstrip structures adapted to be applied to windows having one or more sliding sashes.

Heretofore weatherstrip structures used on windows of this type usually have been in the form of members placed between the face of the frame or jamb and the stiles of the sash. However, such structures were deficient in that they did not allow for any irregularity in the dimensions of the window frame and sashes and while they operated satisfactorily if the parts of the window were perfectly true they would not operate to form a weather-tight engagement between the window frame and sashes if there was shrinkage or if for any other reason the parts of the window became untrue.

Some of these deficiencies were obviated by the construction described and claimed in my previously issued Patent No. 1,511,460 of October 14, 1924, but the construction shown therein was expensive to manufacture and install and was not adaptable for all types of windows.

Therefore, the objects of this invention are to provide a weatherstrip structure for forming a weathertight joint between a sliding sash and the window frame in which it is mounted, which structure will be cheap to manufacture and install; to provide such a weatherstrip structure which will operate as efficiently upon windows which are untrue due to shrinkage or other causes as upon windows which are true; and to provide such a weatherstrip structure which is identified with the parting strip of the window but is separate therefrom.

With these and other objects in mind several embodiments of my invention are fully shown in the accompanying drawings wherein similar characters are used to designate similar parts: Fig. 1 is a transverse sectional view of a fragment of a window near the top thereof upon which one form of my weatherstrip structure has been applied and with the two sashes thereof in a position where they are side by side; Fig. 2 shows diagrammatically the parts of the weatherstrip structure shown in Fig. 1; Fig. 3 is a vertical sectional

view of a fragment at the sill and bottom of a window; Figs. 4, 5 and 6 show details of construction of this form; Fig. 7 is a transverse sectional view as in Fig. 1 of a modified form of weatherstrip structure embodying my invention; Fig. 8 shows diagrammatically the parts of the weatherstrip structure shown in Fig. 7; Fig. 9 is a vertical sectional view of a fragment of a window; and Fig. 10 shows a detail of this modified form.

Referring to the figures and particularly to Figs. 1 to 7, inclusive, the window upon which my new and improved weatherstrip structure is applied has a frame 1 in which a pair of sliding sashes 2 are mounted. The frame 1 has a groove 3 therein and the sashes 2, preferably, have the inner edges of the stiles rabbeted as at 4, all for the purposes more fully hereinafter set forth. My new and improved weatherstrip structure as shown herein includes a member 5 on the frame and members 6 on the sashes. The member 5 on the window frame comprises a base portion 7 which follows the contour of the groove 3 in the frame and is itself formed and adapted to provide a groove to receive the parting strip 8 so that the base portion 7 extends along but is separate from the parting strip 8. This parting strip is preferably of metal as shown in the figures as I have found that such a strip will last longer in use, but as set forth below I do not limit myself to any material. The member 5 also comprises a pair of weatherstrip members which in this embodiment are ribs 9 each of which projects outwardly from the side face of the parting strip 8, as shown. Each of the members 6 carried by a sash has a channel portion 10 which, preferably, follows the contour of a rib 9 so that a sliding weathertight engagement is formed therewith. If any other form of weatherstrip portion is used the portion 10 is changed to form a sliding weathertight engagement therewith.

I prefer that some resilient means such as springs 11 be set between the bottom of the groove 3 in the frame 1 and that part of the base portion 7 of the member 5 which forms the bottom wall of the groove to receive the parting strip 8, for the purpose more fully

outlined below. Each of the springs 11 may be held in position by inserting an end thereof through a slot 18 in the rear wall of the base portion 7 of the member 5, as shown in 5 Fig. 3.

In assembling my weatherstrip structure the weatherstrip member 5 and the springs 11 carried thereby, as described above, are placed in the groove 3 and the parting strip 8 10 is then placed in the groove in the base portion 7 provided to receive it. It will be seen that the parting strip 8 will maintain the member 5 in the desired position and I prefer that the parting strip 8 be held in place by a 15 screw 13 or other means passing therethrough and passing through the bottom wall of the base portion 7 of the member 5 into the frame 1 and I also prefer that only one such supporting means be used and that it be placed 20 near the upper end of the parting strip and weatherstrip member 5. The lower end of the parting strip may be held in position by a clip 14 fastened to the bottom of the frame and I prefer that the clip 14 is slotted as at 25 15 so that the position of the lower end of the parting strip may be adjusted. The weatherstrip members 6 are fastened onto the sash preferably by brads 16 with the channel portion 10 positioned in the rabbets 4. The 30 sashes are then placed in the window so that a sliding engagement is made between the ribs 9 and the channel portions 10. The ribs 9 need not extend from top to bottom of the window or both sides of the parting strip, al- 35 though I prefer that they do, because it only is necessary that each rib is as long as the sash carrying the channel portion 10 in engagement therewith so that a weathertight joint will be formed when the sash is in closed position. 40

If the parting strip and, in turn, the weatherstrip member 5 are supported in this manner and if the screw 13 is not turned down tight, but leaves a play between the bottom of 45 the member 5 and the bottom of the groove 3 the parting strip 8 and the weatherstrip member 5 will be mounted in what may be termed a floating position and when installed on a window will be moved slightly inwardly 50 toward the window frame 1 and the springs 11 will be compressed. If the parts of the window shrink or swell to allow a greater space between the window frame and the sashes the parts of the weatherstrip structure 55 and the parting strip 8 will quickly adjust themselves to any irregularity in the parts of the window.

In the embodiment of my invention shown in Figs. 7 to 10, inclusive, the weatherstrip member 5^a carried by the window frame has 60 the base portion thereof formed in two parts with the overlapping edges 7^a and 7^b forming the bottom wall of the groove to receive the parting strip. This form of weatherstrip is 65 particularly adapted for use on windows hav-

ing parting strips or grooves which are not of standard dimensions because as may be readily seen the member 5^a can be adjusted to various widths of parting strips or grooves without necessitating a different member for 70 each width.

It should be noted that in this embodiment of my invention it is necessary to provide notches 17 extending inwardly from the side of the overlapping edges 7^a and 7^b to receive 75 the supporting screw 13. Likewise, this embodiment of my invention may be quickly and easily applied to windows and when so applied it is not necessary to provide a special parting strip 8, but the old wooden parting strip 8^a may be replaced because the member 5^a may be adjusted to the width of the old strip. When a wooden parting strip is used the springs 11 may be reversed and held in place by a small nail or screw 19 80 passing through the hole 12 in the spring into the parting strip. 85

It may be readily understood that I do not wish to limit myself to the exact details of construction shown in the drawings because 90 the size, shape and arrangement of the various parts and especially the arrangement of the portions which form a sliding engagement between the weatherstrip members 5 and 6 may be varied within wide limits without deviating from the spirit of my invention as included in the claims set forth below. 95

What I claim as new and desire to secure by Letters Patent, is: 100

1. A weatherstrip structure for windows including a member carried by the window frame and extending along the side face of but separate from the parting strip of said window frame and a member carried by the sash; said members being formed and arranged to have a sliding weathertight engagement with one another, and said member carried by the window frame also being arranged and mounted so as to be movable 105 away from or towards said frame whereby said member will adjust itself to any irregularities in the parts of the window when said sliding engagement is made. 110

2. A weatherstrip structure for windows including a member on the window frame and a member on the sash, said member on said window frame comprising a base portion extending along the side face of the parting strip of said window frame and a 115 weatherstrip portion projecting outwardly from said base portion, said member on said sash being formed and arranged to have a sliding weathertight engagement with said weatherstrip portion, and said member on 120 said window frame also being arranged and mounted whereby said weather strip portion thereon is movable away from or towards said frame whereby said member will adjust itself to any irregularities in the parts of the 125 window. 130

window when said sliding engagement is made.

3. A weatherstrip structure for windows including a member on the window frame and a member on the sash, said member on said window frame comprising a base portion extending along the side face of but separate and detached from the parting strip of said window frame and a rib projecting outwardly from said base portion and said member on said sash having a part thereof arranged to follow the contour of said rib so as to have a sliding weathertight engagement therewith.

15 4. A weatherstrip structure for windows including a member on the window frame and a member on the sash, said member on said window frame comprising a base portion having a groove therein formed and adapted to receive a parting strip and a weatherstrip portion projecting outwardly from a side face of said parting strip, said member on said sash being formed and arranged to have a sliding weathertight engagement with said weatherstrip portion, and said member or said window frame also being arranged and mounted whereby said weatherstrip portion thereof is movable away from or towards said frame whereby 25 said member will adjust itself to any irregularities in the parts of the window when said sliding engagement is made.

5. A weatherstrip structure for windows including a member on the window frame and members on the sashes, said member on said window frame comprising a base portion having a groove therein formed and adapted to receive a parting strip and a pair of ribs one of which projects outwardly from 10 each side face of said parting strip, and said member on each of said sashes being formed and arranged to have a sliding weathertight engagement with one of said ribs.

6. A weatherstrip structure for windows including a member on the window frame and a member on the sash, said member on said window frame comprising a base portion having a groove therein formed and adapted to receive a parting strip and a weatherstrip portion projecting outwardly from a side face of said parting strip, said member on said sash being formed and arranged to have a sliding weathertight engagement with said weatherstrip portion, and resilient means 50 set between said window frame and said member thereon.

7. A weatherstrip structure for windows including a member on the window frame and members on the sashes, said member on said window frame comprising a base portion having a groove therein formed and adapted to receive a parting strip and a pair of weatherstrip portions one of which projects outwardly from each side face of said parting strip, said member on each of said sashes be-

ing formed and arranged to have a sliding weathertight engagement with one of said weatherstrip portions, and resilient means set between said window frame and that part of said member carried thereby which forms the bottom wall of said groove.

8. A weatherstrip structure for windows including a member on the window frame and members on the sashes, said member on said window frame comprising a base portion having a groove therein formed and adapted to receive a parting strip, a pair of weatherstrip portions one of which projects outwardly from each side face of said parting strip, and said base portion being formed in two parts with overlapping edges forming the bottom wall of said groove, and said member of each of said sashes being formed and arranged to have a sliding weathertight engagement with one of said weatherstrip portions.

9. A weatherstrip structure for windows including a member on the window frame and members on the sashes, said member on said window frame comprising a base portion having a groove therein formed and adapted to receive a parting strip and a pair of ribs one of which projects outwardly from each side face of said parting strip, and said base portion being formed in two parts with overlapping edges forming the bottom wall of said groove, said members on each of said sashes being formed and arranged to have a sliding weathertight engagement with one of said ribs, and said member on said window frame and said parting strip carried by said groove therein having a single means of support positioned near the upper end thereof and resilient means set between said window frame and said bottom wall of said groove.

In witness whereof I have signed my name to the foregoing specification.
